[57] CLAIM

The ornamental design for the drinking water dispenser, as shown and described.

DESCRIPTION

FIG. 1 is a perspective view of a drinking water dispenser showing my new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a bottom plan view thereof;

FIG. 7 is a rear elevational view similar to FIG. 5, but showing a modified form of my design equipped with rear corner members and refrigeration coils, rather than a rear panel member as shown in FIG. 5; and

FIG. 8 is a bottom plan view of the modified version of my new design shown in FIG. 7.

The left side of my drinking water dispenser is substantially identical to the right side shown in FIG. 3.

FIG. 1FIG. 2FIG. 3FIG. 4

FIG. 5FIG. 7FIG. 6FIG. 8
